E. I. ROGERS, JR

CUFF BUTTON

Filed Feb. 20, 1924

UNITED STATES PATENT OFFICE.

EVERETT IRVING ROGERS, JR., OF PROVIDENCE, RHODE ISLAND.

CUFF BUTTON.

Application filed February 20, 1924. Serial No. 693,992.

To all whom it may concern:

Be it known that I, EVERETT IRVING ROGERS, Jr., a citizen of the United States, and a resident of Providence, in the county 5 of Providence and State of Rhode Island, have invented an Improvement in Cuff Buttons, of which the following description, in connection with the accompanying drawings, is a specification, like characters on the 10 drawings representing like parts.

This invention relates to cuff buttons, and more particularly to cuff buttons of the separable, self-retaining type, wherein there is employed a pair of independent 15 button members adapted to be retained one in each buttonhole of the cuff and having means for connecting or disconnecting the same at will.

The object of the invention is to provide 20 a cuff button in which the separable members may be positively locked together when in position in the cuff, but are capable of separation at will by a simple manual operation, the locking device being such that a 25 button with thin flanges and of pleasing appearance may be produced, while at the same time the locking parts are capable of withstanding all ordinary strains and both members of the button capable of withstanding 30 severe usage without impairment of their functions.

The invention will be best understood by reference to the following description when taken in connection with the accompanying 35 illustration of one specific embodiment thereof, while its scope will be more particularly pointed out in the appended claims.

In the drawings,—

Fig. 1 is a partial sectional elevation 40 showing the two members comprising the cuff button connected together, the drawing being on an enlarged scale and some of the smaller parts being shown of exaggerated thickness for the sake of clearness;

Fig. 2 is a plan view of one of the resilient retainers;

Fig. 3 is a side elevation of the same;

Fig. 4 is a plan view of the complementary resilient retainer;

Fig. 5 is a side elevation of the same;

Fig. 6 is a side elevation of the stud member of the cuff button shown in Fig. 1;

Fig. 7 is an end view of the same;

Fig. 8 is an end view, partly in section, 55 showing the socket member parts; and

Fig. 9 is a sectional elevation of the socket member.

Referring to the drawings and to the embodiment of the invention therein disclosed, I have shown a separable cuff link button 60 comprising independent stud and socket members having the main front or outer heads 11 and 13 respectively. These outer heads are ordinarily provided with ornamental faces which are disposed at the outside of the respective cuff edges when the button is in use. 65

Referring first more particularly to the stud member, the head for the latter is rigidly secured to the shank 15 which, if desired, 70 may be formed integrally therewith, the shank being in the form of a tubular member terminating at its opposite end in the flared plate 17. The latter constitutes the rear wall of the flange for the stud member, 75 the front wall thereof being formed by the plate 19, the peripheral edges 21 of which are joined to the plate 17 by being rolled over the edges thereof. The plate 19 has formed integral therewith a centrally projecting stud having the enlarged head 23 and the necked or shouldered portion 25. To bring the thickness of the flange on the 80 stud member to approximate that of the flange on the socket member, the plate 27 85 may be employed to serve as a filler if desired, or the same may be omitted.

The parts being made of sheet metal, the flange and the parts thereof will be relatively thin and of a lesser thickness than 90 represented in the drawings, where they are shown on an exaggerated scale for the sake of clearness.

Referring now to the socket member, the head thereof is provided with a shank 29 95 similar to the shank 15 and terminating in a substantially flat, flared plate 31, which plate forms the rear wall of the socket member flange. The front wall (see Fig. 9) is formed by a substantially flat plate 33 100 which is centrally apertured at 35, the edge of the aperture being turned inwardly to assist in centering the head of the stud 23 when the latter is inserted therein. When the parts are in position, the outer wall 33 105 of the socket member flange is in firm abutting contact against the substantially flat outer wall 19 of the stud member flange.

The outer edges of the socket flange plate 33 are bent back to form side walls 37 for 110

- the socket chamber and the edges rolled over and back of the edges of the inner plate 31 to unite the two plates into a single structure, the inner plate 31, however, seating 5 against a circumferential shoulder within the side walls 37 so as to be spaced from the outer plate 33 and to leave between the two and around the aperture 35 a thin annular space or chamber.
- 10 Within the socket-flange chamber positive locking means are provided comprising thin, sheet-metal, aperture-forming plates 39 and 41, which herein are formed in two separate complementary pieces adapted to slide one 15 over the other and provide a restricted aperture 43 (see Fig. 8) within which the neck of the stud is adapted to fit snugly so as normally to prevent its withdrawal due to the shouldered head (see Fig. 1).
- 20 The plate 39 has a stud-receiving opening 45 (see Fig. 2), the latter having a curved wall 47 to engage the neck of the stud. The plate 41 has a similar but reversely arranged stud-receiving opening 49, with a similar 25 curved wall 51 to engage the opposite side of the neck of the stud, the two plates 39 and 41 when assembled being reversely arranged so that the stud-engaging portions of the opening 47 and 51 are oppositely disposed.
- 30 At the opposite side of the aperture 45 the plate 39 is connected by the arms 53 and 55 with the neck 57 which is prolonged into a releasing projection 59 adapted to extend 35 through a slot in the walls of the socket flange and project laterally therefrom when the parts are assembled. The tip of the releasing projection may be provided with an enlargement 61 to permit it to be more readily engaged by the fingers for purposes of 40 manipulation.
- Connected to the releasing projection 59 is a pair of curved, resilient arms 63 which, when the parts are assembled in the flange, are confined within the side walls 37 of the 45 flange chamber and tend to urge the locking plate into engagement with the stud if the latter is inserted, or if the stud is absent to draw the locking plates toward each other into the position shown in Fig. 8, reducing 50 the size of the aperture.
- The locking plate 41 is constructed similarly to the plate 39 with respect to the parts 53, 55 and 57, and is provided with a similar releasing projection 59 with an enlargement 55 61 and similar curved, resilient arms 63. The two parts, in fact, may be struck from the same die, but, additionally, the plate 39 has its aperture forming wall 47 raised slightly 60 so that when placed in overlying and reverse relation to the plate 41 the raised portion projects into the aperture 49 of the plate 41 and lies at substantially the same level as the stud-engaging walls 51 in the plate 41.
- 65 In constructing the socket member, the two locking plates are assembled as shown in
- the drawings and placed in the socket-flange chamber. The shank 29 and the plate 33 are then assembled and the edges of the latter rolled over the edges of the flared plate 31. The two locking plates when assembled need 70 have only a sliding fit within the space so that the depth of the chamber and the overall thickness of the flange itself may be very slight. This provides a very thin socket flange and a button very attractive in appearance.
- When the parts are assembled the two sets of curved, resilient arms 63 engage the side walls of the flange chamber and tend to draw the opposite stud engaging walls 47 80 and 51 together, reducing the aperture 43 to a size incapable of passing the enlarged head of the stud. The releasing projections are thus forced outwardly by the resilient arms and project laterally beyond the edges 85 of the socket flange. If the stud is now inserted in the socket member the convex head of the stud forces the two plates apart against the resiliency of the spring arms, enlarging the aperture and permitting the entrance of the stud head, the plates snapping back against the neck of the stud and positively locking the same against withdrawal. By merely pressing the projecting members 59 together, however, the plates may be separated at will and the aperture 43 enlarged 90 sufficiently to permit the withdrawal of the stud.
- When the button is inserted in the cuff and the two parts fastened together, the user 100 may readily insert the thumb and finger between the two sides of the cuff and by pressing them together against the releasing projections effect the release of the stud, the stud automatically withdrawing from the 105 socket, due to the strain which is put on the fabric of the cuff under pressure of the thumb and finger. This not only provides a simple but very convenient method of releasing the positive locking device but an efficient and durable lock.
- Because of the construction employed, the stud can be made short and inconspicuous which adds to the attractive appearance of the button, and at the same time rigid and 115 solid and capable of withstanding considerable rough usage without affecting its function. The two flanges are brought into close abutting relation which not only adds to the thin and attractive appearance of the assembled flanges, but also prevents rocking or upsetting forces which might tend to break the stud loose from its fastening when seated in its socket. The thin locking plates working 120 in the flange of the socket member not only permit the desired thinness of the flange, but provide for engagement of the locking device with the stud relatively close to the base of the latter and close to the mouth of the flange socket which adds to the firmness with 125 130

which the separable parts are held when attached.

While I have herein shown for the purposes of illustration one specific embodiment 5 of the invention, it is to be understood that extensive deviations may be made therefrom and wide changes in the form or relative arrangement of parts, all without departing from the spirit of the invention.

10 Claims:

1. A cuff button having separable members, comprising a stud member having a head and flange separated by an intermediate shank and a rigid stud with a 15 shouldered head projecting centrally from the flange, a socket member having also a head and flange with intermediate shank, the flange presenting a central aperture to receive the stud from the first member, 20 means for positively locking the stud when inserted in the aperture thereby bringing the two flanges into close abutting relation, said means comprising thin sheet metal locking plates one overlying the other and held 25 between opposite faces of the flange, each having a plurality of resilient arms engaging the interior sides of the flange and adapted normally to draw said plates together to present an aperture of lesser 30 diameter than that of the stud head but yieldable to permit the separation of the plates to increase the size of the aperture and permit the passage therethrough of the stud head, and means for manually releasing 35 the stud comprising releasing members projecting laterally from the flange by which the stud locking plates may be forced apart.

2. A cuff button having separable stud and socket members, comprising each a head 40 and flange with intermediate shank, the flange for the socket member having an inner wall and a centrally apertured outer wall separated from the inner wall to leave an annular chamber between the same, devices located within the chamber for positively locking the stud when inserted in the 45 aperture of the flange, the same comprising complementary overlying flat plates presenting a relatively small stud-receiving aperture, said plates being each prolonged 50 on the opposite side of its aperture-forming walls into a releasing projection adapted to extend laterally beyond the edge of the flange and said plates having each a pair 55 of curved resilient arms extending from said prolongation to engage with the sides of the annular flange chamber and draw the plates together but permitting the separation of the same either by insertion of the 60 stud or actuation of the releasing projections to cause enlargement of the aperture.

3. A cuff button having separable stud and socket members, comprising each a head and flange with intermediate shank, the flange of the socket member having a 65 chamber with positive locking means therein comprising complementary aperture-forming plates and a pair of connected resilient means on each plate engaging the walls of the chamber on opposite sides of the plates 70 normally moving the plates to reduce the size of the aperture, and connected releasing projections projecting beyond the edges of the flange to move the plates to increase the size of the aperture. 75

4. A cuff button having separable stud and socket members, comprising each a head and flange with intermediate shank, the flange of the socket member having a chamber with positive locking means therein 80 comprising sheet-metal, aperture-forming members each having two resilient sheet metal connections engaging the walls of the chamber and acting to move the members to a position, where they are adapted to hold 85 the stud positively locked, and radially movable releasing projections secured to said members and extending through the walls of the flange.

5. A cuff button having separable stud 90 and socket members, comprising each a head and flange with intermediate shank, the flange of the socket member having a chamber with positive locking means therein including an aperture-forming plate 95 formed of sheet metal having connected thereto curved resilient arms engaging the opposite sides of the flange chamber, and a releasing projection extending through the walls thereof connected to the said arms. 100

6. A cuff button having separable stud and socket members, comprising each a head and flange with intermediate shank, the flange of the socket member having a chamber with positive locking means therein 105 comprising a pair of complementary aperture-forming plates in sliding contact, each plate having a releasing projection extending through the walls of the flange, a pair of resilient arms connected to the projections and engaging the walls of the flange, each plate having a stud-receiving aperture with walls oppositely arranged in the two plates formed to engage the neck of the stud, the stud engaging walls in one plate 110 being raised to lie in substantially the same plane as the stud-engaging walls in the other plate. 115

In testimony whereof I have signed my name to this specification.

E. IRVING ROGERS, JR.
